(57) **CLAIM**

The ornamental design of a tool caddy, as shown and described.

DESCRIPTION

FIG. 1 is a front elevational view of a tool caddy showing our new design;

FIG. 2 is an enlarged front elevational view thereof;

FIG. 3 is a top view thereof;

FIG. 4 is a front view thereof;

FIG. 5 is a right side view thereof; and

FIG. 6 is a left side view thereof.

The portion of the drawings shown in dashed lines is for illustrative purposes only and forms no part of the claimed design.
